UNITED STATES PATENT OFFICE.

THOMAS A. BRAGG, OF TOLEDO, OHIO, ASSIGNOR TO THE TOLEDO GLASS COMPANY, OF TOLEDO, OHIO, A CORPORATION OF OHIO.

FEEDING DEVICE FOR LEERS.

1,206,807.

Specification of Letters Patent. Patented Dec. 5, 1916.

Application filed January 21, 1909. Serial No. 473,483.

To all whom it may concern:

Be it known that I, THOMAS A. BRAGG, a citizen of the United States of America, and residing at the city of Toledo and county of Lucas, State of Ohio, have invented certain new and useful Improvements in Feeding Devices for Leers, of which the following is a specification, reference being had therein to the accompanying drawings.

10 This invention relates to new and useful improvements in feeding devices for leers, and consists in the construction of a feed-carrier arranged above the plane of travel of the leer-carrier, and which will feed the 15 articles over the leer-carrier and then drop them in rows thereon. The leer-carrier is provided with sockets into which the articles are directed.

The invention further consists in the construction and arrangement in combination of the various parts, all more fully herein-after described and particularly pointed out in the claims.

In the drawings: Figure 1 is a vertical section transversely through the leer, showing an elevation of the feed-carrier and its driving mechanism, and also showing, partly in section, a fire-finishing furnace over which the articles travel; Fig. 2 is a plan view of one section of the carrier-chain; Fig. 3 is a section on line α — α of Fig. 2; Fig. 4 is a horizontal section through the leer showing the feed carrier in plan and partly broken away; Fig. 5 is a vertical section through that portion of the feed-carrier in the furnace and illustrating the actuating devices for opening the holders to discharge the bottles; and Fig. 6 is a longitudinal section through a portion of the leer-carrier illustrating the construction of the holders therein.

1 represents the leer-tunnel formed of the usual brick-work, having therein a carrier which moves from one end to the other. 45 I have shown the carrier as consisting of an endless chain 2 running on the sprocket-wheels 3 and having secured to the links the transverse carrier pans or sections 4 provided with a series of downwardly-tapering 50 sockets or cups 5; these sockets or cups being arranged in transverse rows, as clearly appears in Fig. 4. The sections may be supported at their ends by the wheels 6 running on the tracks 7 at each side of the tunnel.

At the feed end of the furnace I provide 55 above the leer-carrier a track 8 on which runs one flight of an endless chain 9 which runs on the sprocket-wheels 10 at opposite ends. I preferably provide rollers 50 on the chain, running on the track. 60

On each link is arranged a frame 11 (Fig. 2), and on this frame are upwardly-extending lugs 12, there being two pairs of these lugs arranged at opposite sides of the frame, the frame being an open frame and substantially rectangular. Through the lugs 12 extend the pivot pins 13, and on these pivot pins are pivoted sections 14 and 15 of the cups which form the holders, the pivotal connections made between the pins and 70 lugs 16 projecting laterally from the top of each cup section.

Integral with the cup section 15 is the lever 17 having a weight 18 at its outer end, and its inner end is curved so as to extend 75 around the side of the cup section and project out beside the other section. At its end it is provided with a slot in which is engaged a pin 19 on the section 14.

The open meeting edges of the two cup 80 sections, which are substantially cylindrical in cross-section when used for bottles (the construction here shown), are provided with curved faces 20. This construction is such that the action of the weight normally 85 tends to hold the cup sections together, but if the weight is lifted the two sections will turn on these curved faces 20 and open the lower end of the holder and permit the articles to fall therefrom. 90

For the purpose of lifting the weights 18 at the desired time, I provide on each weight a downwardly-extending lug 21. Extending across the leer, just below the path of travel of the lugs 21, is a rock-shaft 22 (Figs. 1 95 and 5), and on this rock-shaft is an arm 23 projecting beneath all the lugs 21 which may be in the leer at any one time. If the shaft 22 is rocked so as to lift the arm 23, it is obvious that the weights 18 above the 100 same will be lifted and the articles in their cups be discharged therefrom.

I have shown this device constructed and arranged to receive bottles as they are dropped from such a machine as shown in 105 the Owens Patent No. 766,768 of August 2, 1904; and in Fig. 1, at 24, I have shown one of the bottles as falling into a funnel 25, the

discharge from which is directly above one of the holders in the feed-carrier, so that the bottle will fall therein.

The feed-carrier and the leer-carrier may 5 be driven from the motor which drives the glass-blowing machine referred to, or they may be timed to operate in connection therewith.

I have shown a shaft 26 projecting from 10 the base 27, which is intended to be the base of the said blowing-machine and which may be driven from the motor thereon. This shaft at its end has a crank 28 to which is connected the pitman 29 guided in the guide 15 30 at its lower end and having a pawl 31 adapted to engage with the teeth on the ratchet-wheel 32 connected to the shaft 33 to which is secured the sprocket-wheel 10 of the feed-carrier. It is obvious that the 20 reciprocations of the pitman 29 will feed forward the feed-carrier one step for each revolution of the crank 28, and being timed with the blowing machine so that immediately after a bottle is dropped therein the 25 carrier will feed forward so as to bring a fresh holder of the cup beneath the spout of the hopper 25.

On the shaft 26 is a pinion 35 meshing with the gear-wheel 36 on a stub-shaft from 30 the base 27, and this gear-wheel carries a pin or finger 37 adapted to strike the arm 38 on the rock-shaft 22; so that in each revolution of the gear-wheel 36 the shaft 22 will be rocked and will then fall back again by 35 gravity to its initial position, as soon as the finger 37 has passed the arm 38.

I have shown a fire-finishing furnace 40 arranged between the receiving-point of the feed-carrier and the leer, so that the bottles 40 in passing over this furnace have their necks fire-finished before entering the leer.

The drive-chains 2 of the leer-carrier as above described are driven by the sprocket-wheels 3 which are secured to the shafts 45; 45 and at one end of the leer this shaft extends through the machine, and any suitable intermittent driving mechanism may be applied thereto so as to feed the leer-carrier forward while the feed-carrier is bringing in a new 50 row of bottles and then to stop the leer-carrier while the cups are opened to discharge the bottles from the feed-carrier and permit them to drop into the sockets in the leer-carrier. I have shown at 49 a clutch mechanism for this purpose, but, as it forms 55 no part of my invention, and as any suitable intermittent drive may be used for this purpose, I do not deem it necessary to describe or explain the same.

60 The parts being thus constructed, their operation is as follows: The bottle machine is run at constant speed and usually delivers a bottle about every four seconds. As the bottles are thus delivered at uniform intervals, it is a simple matter to time the 65

mechanism for carrying out the rest of the operation. As soon as the bottle has dropped into the holder in the feed-carrier, that carrier is moved forward one link by the pawl 31 and the ratchet-wheel 32 and stopped with 70 another empty holder beneath the spout of the funnel 25. As the bottles thus travel from the charging point to the leer in a step-by-step movement, they pass over the fire-finishing furnace 40 and their necks are 75 fire-finished—as, in the construction shown, the necks are downward and project below the carrier-holders. They next pass into the leer and, when a complete row thereof is arranged in the leer above the leer-carrier, 80 each bottle will be above one of the sockets in the transverse row of sockets in the said leer-carrier. At this moment the shaft 22 is rocked, the arm 23 lifted and impinged against all of the lugs 21 above the arm 23, 85 opening the holders in the feed-carrier which are within the leer and allowing the bottles to drop therefrom into the sockets 5 in the leer-carrier sections. The feed-carrier then travels over the sprocket-wheel at the other 90 end and returns to be re-charged, passing in its return-trip beneath the leer, as shown in Fig. 1.

By the construction described it will be observed that the ware is deposited directly 95 from the feed carrier onto the leer carrier as distinguished from the indirect or those structures wherein the ware is first collected on a table or platform and from there shoved or moved onto a leer carrier. It is 100 therefore to be understood that the term direct employed in certain claims has reference to this feature as distinguished from indirect depositing of the material from the feed carrier onto the leer carrier. 105

Having thus described my invention, what I claim as new and desire to secure by Letters Patent is:

1. The combination with a leer, of its carrier having sockets to retain and support 110 the articles thereon, and a feed device for feeding the articles transversely into the leer and depositing them in the sockets.

2. The combination with a leer of its carrier having a series of transverse rows of 115 sockets, and a feed device for feeding in a row of articles and depositing them simultaneously in the sockets.

3. The combination with a leer of its carrier, a feed device for feeding a row of articles across and above the carrier, and means for dropping the articles in a row on the 120 carrier.

4. The combination with a leer, of its carrier having retaining sockets for the articles 125 arranged in transverse rows, a feed carrier moving transversely above the leer-carrier, and mechanism for depositing a row of articles from the feed carrier into the sockets of the leer-carrier. 130

5. The combination with a leer of its carrier, a transverse feed carrier across and above the leer carrier, sockets for holding the articles in said feed-carrier, and means for opening and closing the sockets.
6. The combination with a leer of its carrier, a transverse feed-carrier across and above the leer-carrier, sockets for holding the articles in said feed-carrier, automatic means for opening the sockets while the same are above the leer-carrier, and means for closing the same for re-charging.
7. The combination with a leer having a series of transverse rows of sockets in its carrier, a transverse feed-carrier across and above the leer-carrier, sockets for holding the articles in said carrier, means for intermittently moving the feed-carrier to register a row of filled sockets with the sockets in the leer-carrier, automatic means for opening all the sockets in the feed-carrier which are above the leer-carrier, and means for closing said sockets for re-charging.
8. The combination with the leer and its carrier of the transverse feed-carrier above the leer-carrier, the article holders in said feed-carrier comprising the two pivoted cup sections 15—14 having the curved-bearings 19 at the top, and means for holding the cup sections on the curved bearings to open the bottom.
9. The combination with a leer of a socketed leer carrier therein and means for feeding articles above the carrier and for automatically transferring the articles thereto.
10. The combination with a leer of its carrier having sockets to retain and support articles thereon and means for automatically feeding and transferring a plurality of articles into said sockets.
11. The combination with a leer of a carrier having sockets to receive and support articles thereon and means for automatically feeding articles transversely above said car-
- rier and transferring said articles to the sockets.
12. The combination with a leer carrier, of a ware carrier extending transversely across and above the leer carrier, a charging station below which the ware carrier travels, and means for causing the discharge of groups of ware from the ware carrier onto the leer carrier.
13. The combination with a leer, of its carrier having a series of transverse rows of sockets, a feed-carrier movable transversely across and above the carrier, and means for automatically transferring the articles therefrom to the sockets on the leer-carrier.
14. The combination with a leer having an endless ware-supporting carrier therein, of a ware conveyer entering the leer above the carrier, and connected mechanisms acting automatically to cause the discharge of the ware in groups from the ware conveyer directly onto the leer carrier.
15. In a leer and in combination, a leer carrier having means for receiving individual articles and for retaining them against lateral movement, an article conveyer, and means for causing the articles on the conveyer to be deposited directly into said receivers.
16. In a leer and in combination, a leer carrier comprising a plurality of carrying members, each being provided with spaced ware retainers thereon, each retainer serving to hold individual pieces of ware in position against horizontal movement during its passage through the leer, and means for simultaneously charging a plurality of said ware retainers with ware.
- In testimony whereof I affix my signature in presence of two witnesses.
